UNITED STATES PATENT OFFICE.

WILLIAM A. FRICKE, OF CHICAGO, ILLINOIS.

DISPLAY APPARATUS.

1,222,093.

Specification of Letters Patent. Patented Apr. 10, 1917.

Application filed December 2, 1915. Serial No. 64,785.

To all whom it may concern:

Be it known that I, WILLIAM A. FRICKE, citizen of the United States, residing at Chicago, in the county of Cook and State 5 of Illinois, have invented a certain new and useful Improvement in Display Apparatus, of which the following is a full, clear, concise, and exact description, reference being had to the accompanying drawings, forming 10 a part of this specification.

My invention relates to display apparatus constituting in its preferred embodiment an improvement upon the system disclosed in my co-pending application Serial No. 15 25,356, filed May 3, 1915, and upon the system disclosed in the application of Fred G. Dickerson, Serial No. 64,784, filed December 2, 1915. In my said co-pending application I have disclosed display apparatus 20 comprising elements of differing character that are arranged in sets or groups, the elements in each set being selectable to the exclusion of others in the same set and the sets themselves being selectable.

25 In practising my present invention I am enabled to reduce the switching equipment by employing as many sources of current as there are differing characters of display elements, all as will be fully explained by a 30 description of the preferred embodiment of the invention shown by the accompanying drawings in which Figure 1 is a diagrammatic illustration of a display system equipped in accordance with my invention; 35 Figs. 2, 3 and 4 are respectively plan, side and sectional views of a group of display elements as preferably arranged; Fig. 5 is a detail illustrating the manner of including a metallic pattern and the terminals engaged thereby in circuit; and Fig. 6 is another view more fully illustrating the relative dispositions of the lighting centers and the switching contacts upon a switch board.

Like parts are indicated by similar characters of reference throughout the different figures.

In Fig. 1 I have diagrammatically indicated three display centers at each of which a set or group of four display elements 1, 2, 3 and 4 is located. The display elements may be in the form of variously colored lamps, such as small incandescent lamps, the bulb of lamp 1 being (for example) colored orange; the bulb of lamp 2, white; 55 the bulb of lamp 3, green; and the bulb of lamp 4, red; these lamps being shaded in

the drawings to denote these colors. The sets or groups of display elements are desirably segregated, each set having lamps 1, 2, 3 and 4 being desirably covered by a 60 translucent cap or container 5, clouded glass being suitable material of which to form such cap. Each covering 5 is thus somewhat in the nature of a screen for the lamps behind it to prevent material shifting of 65 the lighting center so far as may be apparent to the observer, the light produced at each set being substantially fixedly localized by the diffusing cover irrespective of the location of the lamp or lamps glowing 70 within the cover. I do not wish to be limited, however, to the employment of the segregating elements. The contact board 6 carries contact terminals 7 (equal in number to the number of groups of display elements, these contacts being disposed similarly to the groups though placed much closer together) for the circuits of the display elements, each terminal 7 being individual to a group of differing display elements 1, 2, 3, 4 and being connected with 75 one terminal of each of such display elements. The other terminal of each display element of each group is connected with a source of current pertaining thereto. 80 Thus each lamp 1 has a terminal connected with a source of current 8 which is common to all lamps 1, each lamp 2 has a terminal connected with a source of current 9 which is common to all lamps 2, each lamp 3 85 has a terminal connected with a source of current 10 which is common to all lamps 3, and each lamp 4 has a terminal connected with a source of current 11 which is common to all lamps 4. The terminals of the 90 generators 8, 9, 10 and 11 that are complementary to the terminals thereof which are connected with the lamps 1, 2, 3 and 4 are respectively connected with connecting devices in the form of plugs 12, 13, 14 and 100 15, which plugs may be used in conjunction with metallic patterns 16, 17, 18 and 19 when these patterns are laid upon the selected terminals 7. The plugs are adapted for separable engagement with the patterns 105 by being engageable therewith as indicated in Fig. 5. Any plug 12 thus coupled with the pattern (18) that is laid upon contacts 7 will cause all orange colored lamps to glow whose contacts 7 are engaged by said 110 pattern. Any plug 13 thus coupled with a pattern (19) that is laid upon contacts 7

will cause all white lamps to glow whose contacts 7 are engaged by this pattern. Any plug 14 thus coupled with a pattern (16) that is laid upon contacts 7 will cause all 5 green lamps to glow whose contacts 7 are engaged by this pattern. Any plug 15 thus coupled with a pattern (17) that is laid upon contacts 7 will cause all red lamps to 10 glow whose contacts 7 are engaged by this pattern.

It will be apparent, from the drawing and foregoing description that a pattern applied upon the contact board will cause lamps in different sets to glow, the selection 15 of the lamps in the sets that are to glow being determined by the generator employed. If it should be desired to have more than one lamp in each set to glow, additional generators corresponding to the additional 20 lamps may be connected with the employed patterns by means of the plugs individual to such generators, on which account each pattern desirably has as many plug receiving openings 20 as there are generators. If 25 it should be desired to have differing portions of the same character displayed in different colors the pattern may be subdivided. Such a subdivided pattern is illustrated by the pattern portions 17, 18 and 19 that coöperate to form the letter R. As these three 30 pattern sections are connected in circuit, according to the drawing, the vertical bar of the letter will be displayed in red, the oblique bar of the letter will be displayed 35 in white, while the curved portion of the letter will be displayed in orange. The letter A, produced by the pattern 16, will all be displayed in green. While I desirably use metallic patterns in the operation of the 40 system of my invention I do not wish to be limited to this form of mechanism for operating selected lamps. For example, the plugs could be applied directly to the selected terminals 7 to select groups of lamps 45 and the lamps in the selected groups which are to be displayed. Inasmuch as the contact terminals 7 are equal in number and are similar in disposition to the groups of

display elements the observer will have presented to his view characters conforming in 50 configuration to the characters defined by the employed terminals 7 whether these terminals be employed in conjunction with the patterns 16, 17, 18 and 19 or by other means.

While I have herein shown and particularly described the preferred embodiment 55 of my invention I do not wish to be limited to the precise details of construction shown as changes may readily be made without departing from the spirit of my invention, but 60 having thus described my invention I claim as new and desire to secure by Letters Patent the following:

1. Display apparatus including a plurality of sets of differing display elements, 65 display elements in each of said plurality of sets being similar to display elements in the other sets; contact terminals for the sets of display elements; sources of current, similar display elements in the sets having one 70 thereof; and means for connecting any of the sources of current with selected contact terminals.

2. Display apparatus including a plurality of sets of differing display elements, 75 display elements in each of said plurality of sets being similar to display elements in the other sets; contact terminals for the sets of display elements, each set of display elements having a contact terminal common 80 to the display elements of such set and connected with one terminal of each of these display elements; sources of current, similar display elements in the sets having one thereof which is connected with the remaining terminal of each of such similar display elements; and means for including any source of current in circuit with selected contact terminals.

In witness whereof, I hereunto subscribe 90 my name this 4th day of August, A. D., 1915.

WILLIAM A. FRICKE.
